UNITED STATES PATENT OFFICE.

HERMAN IHLENBURG, OF PHILADELPHIA, PENNSYLVANIA, ASSIGNOR TO MACKELLAR, SMITHS & JORDAN, OF SAME PLACE.

DESIGN FOR A FONT OF TYPE ORNAMENTS.

SPECIFICATION forming part of Design No. 13,951, dated May 29, 1883.

Application filed April 23, 1883. Term of patent 7 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Types, of which the following is a specification.

The nature of my design is clearly shown in the accompanying typographic impression, to 10 which reference is made; and it consists of a series of type ornaments numbered from 1 to 21, exact representations of which are shown in the typographic impression making part of this specification.

What I claim as my invention, and desire to secure by Letters Patent, is—

The design for a font of printing-type, as shown and described.

HERMAN IHLENBURG.

In presence of—
C. F. HUCH,
HERMAN METIUS.
